(57) **CLAIM**

The ornamental design for a display screen or portion thereof with graphical user interface, as shown and described.

DESCRIPTION

FIG. 1 is a front view of a display screen or portion thereof with graphical user interface showing the claimed design; FIG. 2 is a front view of a display screen or portion thereof with graphical user interface showing a second embodiment; and,

FIG. 3 is a front view of a display screen or portion thereof with graphical user interface showing a third embodiment. The peripheral dashed broken lines illustrate a display screen or portion thereof, and form no part of the claimed design.

1 Claim, 3 Drawing Sheets
